(57) **CLAIM**

The ornamental design for an ice skate blade guard, as shown and described.

DESCRIPTION

FIG. 1 is a first rear perspective view of the ice skate blade guard;

FIG. 2 is a second rear perspective view of the ice skate blade guard;

FIG. 3 is a top view of the ice skate blade guard;

FIG. 4 is a bottom view of the ice skate blade guard;

FIG. 5 is a left-hand side view of the ice skate blade guard;

FIG. 6 is a right-hand view of the ice skate blade guard;

FIG. 7 is a front view of the ice skate blade guard; and,

FIG. 8 is a back view of the ice skate blade guard.

The broken lines are for illustrative purposes only and form no part of the claimed design.
